[57] ABSTRACT

Diagnostics in a peripheral subsystem for a data processing system are performed on a concurrent basis with other programs in the data processing system. The peripheral subsystem has capabilities of generating indications for the data processing system representative of operational conditions that could be encountered; the data processing system is programmed to respond to said indications for diagnosing the operational capabilities of the connected peripheral subsystem. Included in the diagnostics are interface checking between the subsystem and the rest of the data processing system, device status, capability of stacking status, capability of handling nonstackable status, verifying enable/disable operation, and checking device busy status and the like.

BACKGROUND OF THE INVENTION

The present invention relates to data processing systems having peripheral device subsystems and particularly to concurrent diagnostics as between a data processing system and the peripheral subsystem, for concurrently diagnosing the present operational capability of the peripheral subsystem.

Because of equipment complexities and high performance operating capabilities, data processing systems, and particularly peripheral device subsystems, are periodically analyzed for proper operational status and capabilities. Also, when an error is introduced into the data processing system, apparently by a peripheral device subsystem, certain diagnostic procedures should be invoked for diagnosing the cause of the error so that corrective maintenance can be expedited. In most prior systems, diagnostics relating to a peripheral device subsystem, such as a printer system, magnetic tape subsystem, disk system, drum system, communication system, and the like, either require dedication of a central processing unit (CPU) for diagnosing the present operational capabilities of the peripheral device subsystem (control mode) or that the peripheral device subsystem be completely disconnected from the data processing system and be operated in a diagnostic mode by maintenance personnel (off-line mode). The above procedures, while effective to perform the diagnostics and the maintenance, are quite expensive because: (1) the cost per hour of a data processing system is extremely high; therefore, to assign the entire data processing system for maintaining one peripheral device subsystem is a very expensive procedure. (2) Disconnecting a peripheral device subsystem from a data processing system in many instances may require the data processing system to be stopped while the peripheral device subsystem is disconnected. This means additional start-ups and, again, a waste of data processing system total time which becomes expensive. Further, no portion of the peripheral device subsystem is then available for any

usage by the data processing system. Maintenance personnel must slowly diagnose the operational status of the peripheral device subsystem without the assistance of automated analysis generally available through a CPU. While some automatic test equipment may be employed, the analysis performable by a CPU usually is much greater than that which can be performed by test equipment. Again, once the subsystem has been diagnosed, it must be reconnected to the data processing system. (3) While disconnecting a peripheral device subsystem from a data processing system may be effective to diagnose operational status of the peripheral device subsystem, some errors can occur in the interface portion. Such disconnection may or may not detect such error-causing conditions. Accordingly, it is highly desirable that concurrent diagnostics be performed on a peripheral device subsystem by a data processing system.

As used in this application, the term "concurrent mode" indicates that the data processing system has other tasks or jobs in the system that are active and share system facilities with the diagnostic programs and procedures. This does not necessarily indicate that a given CPU will operate simultaneously on a data processing job or task and a diagnostic job or task. Such jobs or tasks may be interleaved within the CPU with the peripheral device subsystem diagnostics being performed simultaneously with data processing systems or other operations being performed by other subsystems or CPU's.

"Quiescent mode" means that all operations with respect to a peripheral device subsystem are complete except those initiated directly or indirectly by an OLT (on-line test) such that the peripheral device subsystem is dedicated to diagnostics initiated by the OLT. The CPU may be still operating in a concurrent mode.

On-Line Test (OLT) — A computer program in a CPU designed to initiate diagnostic procedures in a peripheral device subsystem upon command from an operating system within the CPU. Such OLT's supervise diagnostic procedures.

On-Line Test Executive Program (OLTEP) — The interfacing program between the CPU operating system and OLT's. It is a supervisory program effecting proper sequencing of diagnostics effected by OLT's.

Control Mode — A peripheral device subsystem is entirely dedicated to diagnostics. The OLT responds to all communications with the peripheral device subsystems and operates to the peripheral device subsystem via OLTEP and can act in the supervisory mode. OLT restricts its activities to those devices in the peripheral device subsystem assigned to it by and through OLTEP before entry into the control mode. Entry of control mode usually requires a console entry and an OLT request. Exit from either the quiescent or control mode is by initiation from a request via the console into OLTEP.

Accordingly, for concurrent diagnostic purposes, computer programs have been established including an on-line test executive program (OLTEP) for initiating and supervising concurrent diagnostic procedures. Some of the test requirements to date have required the device being diagnosed to be off-line for effecting a full test of the operating capabilities. Partial tests have been operated on a concurrent mode for a limited number of device operating characteristics. Limited testing on a concurrent basis does not provide sufficient meaning-

ful diagnostic information for minimizing down time of a data processing system. Accordingly, it is very desirable and important that concurrent diagnostic capabilities be enhanced.

SUMMARY OF THE INVENTION

It is an object of this invention to provide enhanced concurrent diagnostic procedures for interface checking, status reporting, enable/disable, tag signals, and the like.

A peripheral device subsystem utilizing the teachings of the present invention includes means for performing signal processing or data processing operations in connection with a data processing system. Additionally, means are provided for generating operating condition indications responsive to channel commands to establish conditions within the subsystem representative of operating conditions not permissible during normal signal processing operations. The above usually follows a SET DIAGNOSE channel command which initiates a diagnostic mode within the peripheral subsystem. Preferably, chaining to an OLT operated CPU is required. During such diagnostic mode, a series of channel commands are issued by the CPU to the peripheral device subsystem forcing stacking status, forcing a falsely indicated control unit busy (CUB) or device busy (DVE BSY), and initiating enable/disable operations and checking response of the peripheral subsystem to nonstackable status as well as to device and I/O controller stackable status. Dedication of the interface between a data processing system and a peripheral device subsystem is performed on a concurrent basis for diagnosing responses and actuations of the peripheral device subsystem with respect to such interface.

The foregoing and other objects, features, and advantages of the invention will be apparent from the following more particular description of a preferred embodiment of the invention, as illustrated in the accompanying drawings.

GLOSSARY OF ABBREVIATIONS AND ACRONYMS

This glossary provides a ready reference to the abbreviations repeatedly used in describing the invention:

ADDR	Address
ADDRI	Address In (a tag signal supplied by an I/O controller indicating address signals appear on CBI)
ADDRO	Address Out (a tag signal

5	BLK UC	indicating address signals are being sent in bus out lines)
	ALU	Arithmetic-Logic Unit
	BKWD	Backward
	BLK INT	Block Interrupt (I/O controller flag blocking SUPPRI)
10	BLK UC	Block Unit Check (I/O controller flag blocking UC status after a burst operation)
	BOC	Branch on Condition
	BOR	Beginning of Record (remains active during entirety of record readback signal envelope)
15	BOT	Beginning of Tape
	CBI	Channel Bus In (lines for carrying data signals from I/O controller to CPU via INTFX)
	CBO	Channel Bus Out (lines for carrying data signals from a channel to an I/O controller)
	CCW	Channel Control Word
	CHNL	Channel
	CMD	Command (a set of control signals)
20	CMDO	Command Out (a tag signal telling an I/O controller to change operation in accordance with predetermined criteria)
	CPU	Central Processing Unit
	CTI	Channel Tag In (a set of lines for tag signals supplied from an I/O controller to a data channel concerning the interpretation of other signals supplied over CBI)
	CTO	Channel Tag Out (a set of lines for tag signals supplied from a data channel to an I/O controller interpreting other signals supplied over CBO)
30	CU	Control Unit; an I/O Controller
	CUB	Control Unit Busy (a tag signal)
	DE	Device End (a tag signal from an I/O device indicating end of an operation)
	DEP	Device End Prime (see below)
	DEPRIME	Device End Prime (a flag signal in a memory unit indicating a data channel has previously requested access to an I/O device. Upon receipt of a device end (DE), signals are supplied to the channel to provide access to the I/O device)
40	DIAG	Diagnostic
	DIAGNOSE	A command ordering an I/O controller to enter a diagnostic mode of operation.
45	FWD	Forward
	GENRST	General Reset
	IBG	Interblock Gap
	IC	Instruction Counter
	IDLEPEND	A wait routine for the channel microprogram unit used to wait for further instructions from a data channel
	IDLESCAN	A microprogram used to scan for DEPRIMES
50	IHS	Information Handling System
	INTF	Interface Circuits
	I/O	Input/Output or Input/Output Device
	IOS	I/O System (a CPU program operating under OS and added to control I/O operations)
55	IR	Instruction Register
	LSR	Local Store Register
	MIS	Multiple Interface Switch
	MPU	Microprogrammable Unit
	MPUX	Microprogrammable Unit No. X (used in connection with a data channel)
	MPUY	Microprogrammable Unit No. Y (used in connection with an I/O device)
60	MTU	Magnetic Tape Unit
	NOP	No Operation (do-nothing command)
	OLT	On-Line Test (a CPU program for exercising and testing a peripheral device connected to the CPU)
	OLTEP	On-Line Test Executive Program (a controlling program for OLT's)

OP	Operation
OPIN	Operation In (a tag signal)
OS	Operating System (a CPU control program)
RES	Reserved
ROS	Read Only Store
RST	Reset
RTN	Return
SDI	Subsystem Device Interface (a multiplexing switch selectively connecting several CU's to a plurality of I/O devices)
SELO	Select Out (a tag signal from channel to CU attempting a selection (connection))
SEL_RST	Selective Reset
SFBKWD	Space File Backward
SFFWD	Space File Forward
SIO	Start I/O (a command initiating an I/O OP)
SPACE OP	An MTU Space Operation (moves or spaces tape)
STAT	Status
STATIN	Status In (a tag signal indicating CBI has a status byte)
STIN	Status In (see STATIN)
STS	Status
SUPPRI	Suppressible Request In (a tag signal)
SUPPRO	Suppress Out (a tag signal)
SVCI	Service In (a tag signal)
SVCO	Service Out (a tag signal)
TACH	Tachometer
TAPE OP	Tape Operation
TCB	Task Control Buffer
TIO	Test I/O
TM	Tape Mark
TU	Tape Unit, also MTU
TUADDR	Tape Unit Address Register
TUBI	Tape Unit Bus In
TUBO	Tape Unit Bus Out
TUTAG	Tape Unit Tag Register
XA	Exchange Register XA
XB	Exchange Register XB
YA	Exchange Register YA
YB	Exchange Register YB

GENERAL PROCEDURE

Referring now to FIG. 1, the general procedure followed by a data processing system and a peripheral device subsystem for effecting concurrent diagnostics using the present invention is explained. First, a CPU at 100 supplies a SET DIAGNOSE channel command to the peripheral device subsystem for initiating diagnostic mode in the connected subsystem. It then forces the subsystem to be chained to the DIAGNOSE command such that no other data processing system can interrupt the diagnostic procedures and thereby introduce errors inadvertently into the interrupting data processing system. The SET DIAGNOSE command is initiated by an OLT via OLTEP to a channel processor. The subsystem is responsive to the command and its CCW to establish a diagnostic mode in accordance with the CCW as has been well known. Upon completion of step 100, the peripheral device subsystem is ready to perform concurrent diagnostics.

CPU then sends diagnostic commands to the peripheral subsystem at 101. This includes forced indications in the I/O controller with regard to I/O devices, the control unit (CU), and to an MIS (multiple interface switch). Other indications, as well, may be forced for indicating operating status for diagnostic purposes, as will become apparent. At the end of step 101, the peripheral device subsystem has been set for diagnosing responsiveness to selected input/output commands and operational status with respect to certain selected channel commands.

The CPU then supplies one or more chained I/O commands at 102. At 103, after the connected peripheral device subsystem has responded to the I/O com-

mands supplied at 102, the CPU checks the forced indications and command responses for diagnostic purposes. In accordance with the OLT, steps 102 and 103 may be repeated. Alternatively, step 101 may be reinitiated for performing a second concurrent diagnostic procedure. Chaining may be maintained as steps 101, 102, and 103 and repeated for different operating diagnostics. It may be desirable for fully utilizing the concurrency of the diagnostic procedures to break the chaining at 104 for permitting interleaved data processing operations. That is, the concurrent diagnostics may be performed in connection with one or two peripheral devices. The other devices are available for data processing operations, and it may be desirable to interleave the diagnostics with the data processing operations at the subsystem level in order to reduce diagnostic cost to the data processing system. Accordingly, when the chain is broken at 104, other programs within the operating system or other data processing systems connected to the peripheral device subsystem can initiate data processing operations. After the chain is broken at 104, step 100 may be repeated for a subsequent diagnostic, with the steps 100, 101, 102, and 103 also repeated. Finally, after the concurrent diagnostics, as requested by an initial program load (IPL) operating through OLTEP, the status is logged in CPU at 105 and probably printed out for use by maintenance personnel assigned to the data processing subsystem. The programming exits at 106 completing the diagnostic task.

SYSTEM ORGANIZATION

Referring to FIG. 2, the environment in which the present invention may be practiced is shown in simplified form. CPU 110 has an operating system such as OS/360 or OS/370 at 111. OS is an executive which calls in object programs 112 for performing data processing operations, as is well known. The input/output program module 113 (IOS) program connects a channel processor 114 to OS 111 for effecting input/output operations. Channel processor 114, in turn, communicates with one or more peripheral subsystems 115 which performs the actual I/O operations. The peripheral subsystem additionally, through MIS, is connectable to another CPU 116 which is organized in the same manner as CPU 110. Additionally, CPU 110 has a set of diagnostic programs 117 which includes 35 OLTEP and a set of OLT's. The OLT's may be resident on a disk subsystem (not shown) and callable into magnetic core memory of CPU 110 upon initiation by an IPL. Once an OLT is resident in CPU 110, it calls in operation of peripheral subsystem 115 through the programmed and hardware chains just described. The OLT controls CPU 110 just long enough to initiate operations of peripheral subsystem 115 during a diagnostic mode. During such diagnostic mode, channel processor 114 may be dedicated to the diagnostic procedure. Additionally, CPU 110 may have a plurality of such channel processors. In the alternative, channel processor 114 may service several I/O subsystems with each subsystem being, in turn, dedicated to an I/O function such as concurrent diagnostic or a data processing operation. Each channel processor 114, of course, services several peripheral subsystems, only 40 45 50 55 60 65 one of which is shown in FIG. 2.

PERIPHERAL SUBSYSTEM HARDWARE CONFIGURATION

Referring now to FIG. 3, the interface circuits between CPU's 110 and 116 and the peripheral device subsystem, including I/O controller 11, are shown in simplified logic form. Portions of the interfacing circuits pertinent to the practice of the invention are brought out in some detail, while the other interfacing circuits not pertinent to the practice of the present invention, but necessary for effecting interfacing, are shown as a single block in each section. The circuitry represented by logic blocks 150 and 151, respectively, in interface A and B circuits 152 and 153, has been used before in a similar two-channel connection between I/O controller 11 and a pair of channels 114 and 118. Interface circuits A and B are connected to controller circuits 154 (FIGS. 4 and 5) via "MIS" (multiple interface switch) 155. MIS 155 selectively connects circuits 154 to CPU 10 via interface A circuits 152 and channel (A) 114, or to CPU 116 via interface B circuits 153 and channel (B) 118. Additionally, a neutral position is employed. Channels A and B are connected to other peripheral systems in accordance with known data processing techniques.

I/O controller 11 is connected to a plurality of I/O devices via a set of cables 12 through a subsystem device interface (SDI) 157. SDI 157 may be constructed in accordance with the teachings of the patent to E. W. Devore, U.S. Pat. No. 3,372,378. In accordance with that patent, additional controllers 158 and 159 are selectively connectable to the plurality of I/O devices through SDI 157. In turn, CU's 158 and 159 may have separate MIS's for connecting to a plurality of CPU's 160.

In accordance with known data processing techniques, any of the CPU's 110, 116, or 160 can connect to any of the I/O devices via SDI 157. In practicing the present invention in the illustrated environment, concurrent diagnostics on any of the I/O devices and CU's 11, 158, and 159 may be initiated and supervised by any of the connected CPU's. That is, two of the CPU's 160 may perform diagnostics on CU 158 on a concurrent basis with other tests in the respective CPU's. Additionally, because of SDI 157, such CPU's can perform concurrent diagnostics with respect to any of the I/O devices connected to SDI 157. In a similar manner, CPU's 110 and 116 can, on a concurrent basis, perform diagnostics on I/O controller 11 and any of the I/O devices. The same is applicable to CU 159 and the other CPU's 160.

Before proceeding to the description of the portion of the logic pertaining to practicing the invention in the illustrated environment, the operation of MIS 155 as presently employed in several data processing systems is briefly described. The function of MIS 155 is that of a multiple-pole, triple-throw switch 165. Effectively, all of the buses and cables interconnecting channels 114 and 118 with I/O controller 111 are switched by 165 through electronic means of known design. In a first position at A, switch 165 interconnects channel 114 to I/O controller circuits 154. At position C (the neutral position), circuits 154 are disconnected from channels 114 and 118. At position B, channel 118 is connected to circuits 154. Switch 165 is actuated by request from channels 114 and 118 as initiated by CPU's 110 and 116. Since CPU's 110 and 116 operate asynchronously,

two requests can be received by MIS 155 at the same time. MIS has priority circuit 166 for assigning priority to one of the two requests. The requests are manifested in the illustration by a select out (SELO) tag signal supplied by channels 114 and 118, respectively, over cables 168 and 169. SELO is supplied from those cables to priority circuit 166 via lines 171 and 172. Additionally, SELO is also supplied to logic circuits 150 and 151 as will become more apparent. Priority circuit 166 responds to SELO on lines 171 and 172 to selectively set selector latch 173 and reset neutral indicating latch 174. For example, if latch 174 is in the active condition, switch 165 is to terminal C. Upon receiving SELO, priority circuit 166 resets latch 174 to the inactive condition and simultaneously sets latch 173 either to A or B for selectively moving switch 165 to the A or B terminals thereby connecting one of the two interfaces to circuits 154. In the illustrated system, interface A has priority; hence, if two SELO's are received simultaneously, priority circuit 166 sets latch 173 to condition A. As a result of this selection, an initial selection sequence for channel 114 is performed by circuits 154. A control unit busy (CUB) signal is supplied to channel 118 indicating the subsystem is not available. Upon completion of an I/O operation, circuits 154 through microprogram means supply a control signal over cable 176 and thence line 177 setting latch 174 to N, thereby moving switch 165 to terminal C. The condition of latch 173 then is ignored until another SELO is received by priority circuit 166. Under chained operations, circuits 154 are inhibited from setting latch 174 to the active condition, hence, maintaining the operational state of latch 173 in accordance with its setting by circuits 166.

Once MIS 165 has been actuated to terminal A or B, SELO is supplied through switch 165 to cable 179, hence, over line 180 to microprocessor circuits within circuits 154 as later described for trapping same to an initial selecting sequence. SELO also travels to interface A and B circuits 152 and 153, logic 150 and 151.

Circuits 154, which include a microprocessor, in response to SELO trap on line 180 supply an address in (ADDR) initiating signal over cable 176 to either interface circuits 152 or 153 in accordance with switch 165 setting. The respective logic circuits 150 and 151 generate the ADDR signal for supplying it to the respective channels. Simultaneously, the CUB latches 182 and 183 in the other interface circuits are set to the active condition. These latches supply an activating signal to the encoding circuits 184 and 185 which supply CUB to the respective channels. Encoders 184 and 185 are actuated by a later-described status in (STATIN) signal generated by activity in circuits 154. STATIN indicates that the set of signals on channel bus in (CBI), later described, indicates the status of the response of the I/O subsystem to a request by the activating channel. In this regard, both interface circuits 152 and 153 include STATIN generators 188 and 189 which generate code permutations for CBI, respectively, for channels A and B in response to instructions received from circuits 154. STATIN is simultaneously supplied with the code permutations for indicating status of the subsystem.

STATIN generators 188 and 189 generate the STATIN signal through OR circuits 190 and 191. In usual data processing operations, logic circuits 150 and 151

respectively generate the STATIN signals. In certain situations, AND circuits 192 and 193 generate a STATIN signal. Switched SELO on line 180 is one input to both AND circuits. This indicates that the STATIN tag is generated in response to the SELO after MIS 155 has assigned priorities and effected operations of switch 165; i.e., STATIN is not generated until circuits 154 can be connected to the selecting channels. The other inputs to AND circuits 192 and 193 are respectively supplied by OR circuits 194 and 195.

One input signal to both OR circuits 194 and 195 is supplied over lines 197 and 198 entitled "ARM CUB." ARM CUB enables a CUB response to a channel to which the subsystem is chained. Under normal operations, CUB can never be issued to a channel to which the subsystem is chained. This is a technique in concurrent diagnostics enabling a CPU, through its channel, to verify operation of the CUB circuits in the subsystem.

STATIN is also activated whenever circuits 154, either upon their own initiation or upon receipt of a channel command (including a CCW), perform a general or selective reset. During such a reset operation, an activating signal supplied respectively over lines 200 or 201 to supply STATIN to the initiating channel such that the status, as a result of the reset, can be supplied over CBI for analysis by the respective CPU's. Additionally, STATIN is generated in response to an SELO for presenting initial status over CBI as detected by AND circuits 202 and 203, respectively, for the two interfaces. These AND circuits are responsive to AB latch 173 being in the appropriate signal state, latch 174 indicating a not neutral connection of switch 165, and a STATIN generating signal received from circuits 154.

I/O CONTROLLER 11 AND ITS RELATIONSHIP TO THE SYSTEM

I/O controller 11 operates with the channel described in the Moyer et al., U.S. Pat. No. 3,303,476. FIGS. 1 and 3 of that patent describe all tag signals used herein except SUPPRESSIBLE REQUEST IN which is defined with respect to MUX (channel MPU) microprograms. It also assumes that the interface between the controller and the I/O devices follows a similar busout, but-in, tag-line arrangement. In addition to the functions described in the Moyer et al. patent *supra*, a tachometer input line is provided to I/O controller 11, as later described.

The term "CPU" is hereafter used to include the channel portions of data processors. I/O controller 11 provides control for exchanging informationbearing signals between CPU's and I/O devices, such as magnetic tape units (MTU's) via cable 12 (FIG. 4).

I/O controller 11 has three main sections. MUX is a microprogrammable unit (MPU) providing synchronization and control functions between the I/O controller 11 and channels 114 and 118. MUY performs similar functions with I/O devices via SDI 157. In a magnetic tape subsystem, MUY provides motion control and other operational related functions uniquely associated with the I/O device. The third section is data flow circuits 13, which actually process the information-bearing signals. Data flow circuits 13 may consist of entirely a hardware set of sequences and circuits for performing information-bearing signal exchange operations. In an I/O controller associated with a magnetic

tape recording system, such data flow circuits include writing circuits for both PE and NRZI, readback circuits for both encoding schemes, deskewing operations, certain diagnostic functions, and logging operations associated with operating a magnetic tape subsystem.

Since MUX and MUY are independently operable, each having its own programs of microinstructions, program synchronization and coordination are provided. To this end, MUX has exchange registers 14 while MUY has exchange registers 15. The signals from the MPU's temporarily stored in these registers are supplied directly to data flow circuits 13 for effecting and supervising data flow and signal processing operations. Additionally, such signals are simultaneously provided to the other MPU. That is, register 15 supplies MUY output signals to MUX and register 14 supplies the MUX output signals to MUY. The respective MPU's under microprogram control selectively receive such signals for program coordination.

The channels exchange control signals with MUX over CTO (channel tag out), CTI (channel tag in), CBO (channel bus out), and CBI, plus trap control line 17. When the trap line is actuated, MUX aborts all present operations and branches to a fixed address for analyzing signals on CBO. These signals force MUX to perform channel commands or selected functions. In a similar manner, MUX has trap control line 18 extending to MUY. MUY responds to an actuating signal on line 18 from MUX in the same manner that MUX responds to a trap signal on line 17. MUY, in addition to exchanging control signals with I/O devices, also has trap line 21 for controlling an I/O device in a similar manner. All information-bearing signals are processed through data flow circuits 13 via full-duplex cables 23 and 24.

Data flow circuits 13 have CBI lines 30 and CBO lines 31. Each set of lines has a capability of transferring one byte of data plus parity. Similarly, tape unit bus in (TUBI) lines 32 transfer signals to data flow circuits 13 and MUY to the I/O devices via SDI 157. Tape unit bus out (TUBO) lines 33 carry information-bearing signals for recording in MTU's plus commands from MUY and MTU addresses from MUX. Status signals are supplied both to MUX and MUY over status cables 34 and 35. Velocity or tachometer signals supplied by the selected and actuated MTU are received over line 36 by MUX, MUY, and data flow circuits 13.

MUX has output bus 40 (also termed B bus) supplying signals to its exchange registers 14. These include branch control register 41, register XA, and register XB. Output bus 40 is also connected to the channel exchanging registers 42. These registers are CTI and CBI. CBI is channel bus in, while CTI is channel tag in. CTI transfers the tag signals from I/O controller 11 to CPU as described in the Moyer et al. patent and other control signals for interfacing operations.

Additionally, CBO gate 43 receives bytes of data for data flow circuits 13 and for MUX. Gates XA and XB similarly gate exchange signals from the MUY exchange registers 15. Gate XA receives the control signals from register YA while gate XB receives exchange signals from register YB. CBI register is shared by MUX and data flow circuits 13. The CBI lines are multiplexed in accordance with the Moyer et al. patent.

CTI supplies tags indicating what the bus in signals mean.

Signals in TUBO register output lines 33 are interpreted by the MTU's in accordance with the signals in TUTAG (tape unit tag) register.

External signals are supplied to MUX and MUY via external registers 50 and 51, respectively. Such external signals may be from another I/O controller, from a maintenance panel, communication network, and the like. Also, hardware detected errors are lodged in register 52 for sampling by MUX.

I/O controller 11 has an efficient initial selection process. MUX responds to a channel SELO request for service of an MTU to provide the MTU address over output line 40 into TU address register 60; from there, the address is sent to all MTU's. The appropriately addressed MTU responds to MUY that the selection is permissible or not permissible. If permissible, a connection is made; MUY notifies MUX via register YA. MUX then completes the initial selection by responding to the requesting channel via CTI and MIS 155. Data processing operations then ensue.

MICROPROGRAMMABLE UNITS (MPU'S)

The MPU's contain microprograms which determine the logic of operation of I/O controller 11. MUX contains a set of microprograms in its control memory designed to provide a responsiveness and data transfers with the channels. In a similar manner, MUY contains a set of microprograms for operation with the various MTU's. Registers 14 and 15 contain signals from the respective microprograms which serve as inputs to the respective programs for coordinating and synchronizing execution of various functions being performed. A better understanding of how the microprograms operate the hardware is attained by first understanding the logic construction of the MPU's which are constructed in an identical manner.

Referring more particularly to FIG. 5, an MPU usable in I/O controller 11 is described in a simplified block diagram form. Data transfers are serially in bytes of eight bits each. The microprograms are contained in read only store (ROS) control memory 65. While a writable store could be used, for cost-reduction purposes, it is desired to use a ROS type of memory. The construction and accessing of such memories are well known. The ROS output signal word, which is the instruction word, is located by the contents of instruction counter (IC) 66. IC 66 may be incremented or decremented for each cycle of operation of MPU. By inserting a new set of numbers in IC 66, an instruction branch operation is effected. The instruction word from ROS 65 is supplied to instruction register (IR) 67 which staticizes the signals for about one cycle of operation. The staticized signals are supplied over cables 68 and 69 to various units in MPU. Cable 68 carries signals representative of control portions of the instruction word, such as the operation code and the like. Signals in cable 68 are supplied to IC 66 for effecting branching and instruction address modifications. Cable 69, on the other hand, carries signals representative of data addresses. These are supplied to transfer decode circuits 70 which respond to the signals for controlling various transfer gates within MPU. The other portions of the signals are supplied through OR circuits 71 to arithmetic logic unit (ALU) 72. In ALU 72, such signals may be merged or arithmetically combined with

signals received over B bus 73 for indexing or other data processing operations. MPU has local store register memory (LSR) 75 accessible in accordance with the address signals carried over cable 68. Address check circuit 76 verifies parity in the address. The address signals may also be used in branch operations. AND circuits 77 are responsive to transfer decode signals supplied from circuits 70 through AND circuits 78 to transfer the address signals in an instruction word to IC 66. Such transfer may be under direct control of the operation portion of the instruction word as determined by transfer decode circuits 70 or may be a branch on condition (BOC) as determined by branch control circuits 79 which selectively open AND circuits 77 in accordance with the conditions supplied thereto, as will become apparent.

The data flow and arithmetic processing properties of the MPU center around ALU 72. ALU 72 has two byte inputs, the A bus from OR circuits 71 and B bus 73. ALU 72 supplies output signals over cable 80 to D register 81. D register 81 supplies staticized signals over D bus 82 to LSR 75. Instruction decode circuits 83 receive operation codes from IR 67 and supply decoded control signals over cable 84 to ALU 72 and to AND circuits 78 for selectively transferring signals within MPU.

ALU 72 has a limited repertoire of operations. Instruction decode 83 decodes four bits from the instruction word to provide 16 possible operations. These operations are set forth in the Instruction Word List below:

TABLE I

Instruction Word List

Op Code	Mnemonic	Function
0	STO	Store constant in LSR A set to 0
1	STOH	Store constant in LSR, indexed addressing
2	BCL	Match with Field 1, branch to Addr in Field 2
3	BCH	Match with Field 1, branch to Addr in Field 2
4	XFR	Contents of one selected LSR location is transferred to selected register or selected input is gated to one selected LSR location
5	XFRH	See XFR above plus indexed addressing
6	BU	Branch to 12-bit ROS address in instruction word
7	00	Not used - illegal code
8		A OR'd with B, result stored in LSR 75
9	ORM	A OR'd with B, result not stored
A	ADD	A plus B, sum stored in LSR 75
B	ADDM	A plus B, sum not stored
C	AND	A ANDed with B, result to LSR 75
D	ANDM	A ANDed with B, result not stored
E	XO	A EXCLUSIVE OR B, result to LSR 75
F	XOM	A EXCLUSIVE OR B, result not stored

In the above list, the letter "A" means A register 85, "B" is the B bus, and the mnemonics are for programming purposes. The term "selected input" indicates one of the hardware input gates (92, 94, 96, 98) to the ALU output bus 80. The term "selected register" indicates one of the "hardware" registers in MPU. These include the interconnect registers 14 and 15 (FIG. 4), tag register 74, bus register 99, address register 60, and

IC 66. Note that the transfers from LSR 75 to these selected registers are via B bus 73. In FIG. 4, the B bus for MPUX corresponds to cable 40, while the MPUY B bus is cable 40A. Registers 14 receive signals via AND circuits 86 and 87. In MPUY, AND circuits 86 and 87 supply signals to exchange registers 15. Branch control 79 in FIG. 5 is the internal branch control. Branch controls 41 and 41A of FIG. 2 supply their signals respectively over cables 88 and 87A to the respective MTU's. These branch controls are separate circuits. Tag register 74 in FIG. 3 for MPUX corresponds to CTI register in the channel exchange registers 42. For MPUY, it corresponds to TUTAG register connected to SDI 157. In a similar manner, bus register 99 for MPUX is register CBI in channel exchanging registers 42, while in MPUY it is register TUBO. Address register 60 of FIG. 5 corresponds to TU address register 60 of FIG. 4. MPUY address register 60 is not used.

Status register 89 has several output connections from the respective MPU's. It is divided into a high- and low-order portion. The high-order portion has STAT (status) bits 0-3, while the low-order portion has STAT bit 0 plus STAT bits 4-7 (referred to as STAT A through STAT D, respectively). The low-order portion is supplied to the branch control 79 of the other MPU's. The bits 0 and 4-7 are supplied to the data flow. Bit 7 additionally is supplied directly to the ALU 72 of MPUY as indicated by lines 90 in FIG. 4. This corresponds to a self-trapping operation which will be later described. Interpretation of the STAT bits is microprogram determined.

The signal-receiving portions of each MPU are in four categories. First, bus register 91 is designed to receive tags and data bytes for MPUY; this corresponds to CBO register 43 of FIG. 4. An MPUY bus register 91 is TUBI register. AND circuit 92 is responsive to the transfer decode signals from circuits 70 to selectively gate bus register 91. From thence, the data bytes are supplied to LSR 75. Secondly, D register 81 also receives inputs from hardware error register 93 via AND circuits 94. Hardware error signals (parity errors, etc.) are generated in circuit 95 in accordance with known techniques. Thirdly, AND circuits 96 receive external data signals over cable 97A for supplying same to D register 81 under microprogram control. Fourthly, interchange registers 14 and 15 respectively supply signals to pairs of AND circuits 98 which selectively gate the interchange signals to D register 81 under microprogram control. The receiving microprogram controls the reception of interchange signals from the other MPU.

Generally, the outgoing signals from each MPU are supplied via B bus 73, also a main input bus to ALU 72. The signal-receiving bus is the D bus, which is the input bus for LSR 75 and the output bus for ALU 72.

Since ALU 72 has a limited repertoire of operations, many of the operations performed are simple transfer operations without arithmetic functions being performed. For example, for OP code 4, which is a transfer instruction, the contents of the addressed LSR are transferred to a selected register. This selected register may be A register 85 in addition to the output registers. To add two numbers together in ALU 72, a transfer is first made to A register 85. The next addressed LSR is supplied to the B bus and added to the A register contents with the result being stored in D register 81. At

the completion of the ADD cycle, the contents or result of D register 81 are stored in LSR 75. If it is desired to output the results of the arithmetic operation, then another cycle is used to transfer the results from LSR 75 over B bus 73 to a selected output register such as one of the interchange registers or bus register 99.

In FIG. 5, the input to D register 81 is either cable 44 or 44A of FIG. 4. Hardware error circuits 95 and error register 93 of FIG. 5 correspond both to the hardware error circuits 52 and 52A of FIG. 4. External cables 97A receive signals from the external registers 50 and 51 respectively for the two MPU's.

AND circuits 98 of FIG. 5 correspond to the gates XA, XB, YA, and YB of FIG. 4.

Each MPU is trapped to a predetermined routine by a signal on trap line 17 or 18, respectively; the trap signal forces IC 66 to all zeroes. At ROS address 000, the instruction word initiates X-trap routine or Y-trap routine (FIG. 6). For reliability purposes, it is desirable to force MPUY to inactivity. This means that clock or oscillator 48 is gated to an inactive state. During normal operations, clock 48 supplies timing pulses to advance IC 66 and coordinate operations of the various MPU's as is well known. Whenever MPUY has finished its operations, it sets STAT D in register 89. STAT D indicated MPUY has finished its operations as requested by MPUX. The STAT D signal sets hold latch 99A indicating that MPUY is inactive. Hold latch 99A gates clock 48 to the inactive condition. When MPUX traps MPUY, not only is IC 66 preset to all zeroes, but hold latch 99A is reset. Clock 48 is then enabled for operating MPUY.

MICROPROGRAMMING GENERALLY

FIG. 6 shows general relationships between the micro-routines of MPUX and MPUY. This showing is greatly simplified to give a general impression of how the micro-routines cooperate to perform I/O controller functions. Many of the functions performed by these micro-routines have been performed before in other I/O controllers, usually by hardware sequences. Some micro-routines of lesser importance to the present invention have been omitted for clarity. The described routines were selected to illustrate the operating relationships of MPUX, MPUY, data flow circuits 13, MTU's, and CPU in evaluating subsystem performance by concurrent diagnostics as more clearly brought out later.

X-idlescan 120 and Y-idlescan 121 monitor pending status, interrupt status, and provide intercommunication between the two MPU's for ascertaining availability of the I/O devices. X-idlescan 120 includes trapping MPUY via Y-idlescan 121 for polling I/O devices via SDI 157 to determine availability of an addressed MTU. Included in X-idlescan is a wait routine which idles MPUX until trapped by a channel. The channel traps MPUX to ROS 65 address 000. At MPUX ROS address 000, X-trap 122 begins. During the execution of X-trap routine 122, MPUY is trapped to ROS address 000 to later execute Y-trap routine 123. In X-trap 122, CTO is sensed for initial selection. If the initial selection tag is active, X-trap routine branches the microprogram to X-initial selection 125. If there is no initial selection, then either X-RESET 126 or an ALU diagnostic within diagnostic routine 127 is performed. Diagnostic routine is shown in part in flowchart form in FIG. 7. Upon completion of these functions, X-idlescan

120 may be re-entered to complete MTU scanning operations. Initial selection 125 is responsive to certain hardware errors received at 128 (sensed as described with respect to FIG. 3) to stop I/O controller 11 for indicating detected hardware errors.

During an initial selection, X-polled 129 is entered to further identify the channel request. Also, certain branch conditions are set up in LSR for use later by X-termination 130. MTU address verification may be performed. Upon completion of the branch setups, the X-polled 129 initiates X-status 132. X-status 132 activates CTI to send tag signals to the channel interface indicating controller status in response to the previously received requests. Based upon the branching set up in X-polled 129, the microprogram execution may follow several routes. These primarily end up in X-termination 130 which terminates the MPUTX operation. MPUTX then scans for further interrupts. With all scanning completed, MPUTX waits for further instructions from either channel 114 or 118.

Another routine is service return (SERVRTN) 135 used in conjunction with the channel interface circuits 152 and 153 for timing and control purposes during data transfers. The operation of the above-referred-to data channel in Moyer et al. is implemented by SERVRTN 135. Another possible routine entered from initial selection 125 is X-mode 136, which determines the mode of operation in the controller in response to channel CMDO (command out) signals. X-read type and test 137 is entered in the event the initial selection 30 results in a read operation. X-read type and test 137 traps MPUTY to predetermined ROS control memory addresses for initializing a read operation, within MPUTY. In a similar manner, X-write 138 is entered and also traps MPUTY to another subroutine for initializing a write operation. Error status 139 transfers error information to CPU. This routine is closely associated with initializing I/O controller 11 for read and write. Sense 140 is entered in response to a channel sense command. Sensing transfers sense bytes to CPU for analysis. X-termination 130 also traps MPUTY in connection with the selecting activated MTU's and for performing other functions in connection with terminating an operation previously initiated through a channel. MPUTY micro-routines respond to MPUTX microroutines for controlling various MTU's via SDI 157. These micro-routines also transfer information control signals, I/O devices, and SDI 157 to MPUTX for retransmital to channel and CPU. Upon being trapped by MPUTX, Y-trap 123 obtains an MPUTY ROS address from XB register and then branches to that address. Such ROS addresses are the first instruction address of several MPUTY microprograms. For example, one address initiates diagnostic 142. Diagnostic 142 may initiate one of several microprograms for effecting operations in CU 11 or an MTU for diagnostic purposes. Such program connections are not shown.

On the other hand, Y-trap routine 123 may branch to Y-initial selection 148 to initialize MPUTY for activity set forth in additional control signals from MPUTX in registers 14. This may include an initiation of status 149, termination 147, or Y-idlescan 121. The MTU operating routines 143-146 may also be initiated from initial selection 148. In addition to exchanging control signals via registers 14 and 15, status information is freely exchanged between the two MPU's for microprogram coordination.

MICROPROGRAM SEQUENCE FOR MPUTX ENABLING CONCURRENT DIAGNOSTICS

A simplified flowchart later shows microprogram flow for setting and sensing chained and diagnostic flags effecting concurrent diagnostics. MPUTY microprograms are subservient to the described microprogram for effecting certain diagnostic functions not necessarily associated with enabling concurrency and, therefore, are not described. LSR 75 in MPUTX retains diagnostic and operating flags upon which the microprograms branch to various sequences for effecting the designated concurrent operations. For ease of reference, a partial LSR map for control flags in MPUTX LSR 75 is set forth below:

TABLE II

Selected Diagnostic Flags		
Register and Bit	Flag	
4-0	DIAG MODE	
4-1	BLK INT	
4-2	FORCE DVE BSY	
4-3	ARM CUB	
4-4	BLK UC	
4-5		
4-6		
4-7		

Selected Operation Flags		
Register and Bit	Flag	
5-0	CHAIN A	
5-1	CHAIN B	
5-2	REW/DSE	
5-3	OP COMPLETE	
5-4	UNIT CHECK	
5-5	ENABLE	
5-6		
5-7		
6-0	OPIN	
6-1	STATIN	
6-2	CUB-A	
6-3	CUB-B	
6-4	ADDRI	
6-5	SVCI	
6-6	CUR	
6-7	DE	
7-0	DEPRIME	
8-0	DEPRIME	

In the flowchart below, each major sequence step is listed, followed by the description. Entry to the various sequence steps is from the immediately preceding step unless otherwise indicated after the word "Enter." Exit from the sequence step is to the immediately following listed sequence step unless otherwise indicated. The function is described in abbreviated form indicating the function performed during the particular step. That is, each step represents several micro-instructions in MPUTX, the exact code listing being one of programming design not necessary to practicing the present invention. Following the flowchart, a brief description ties selected steps of the microprogram flowchart into the functions performed for concurrent diagnostics. Reference to particular steps in this flowchart will be by reference to sequence step number.

SEQUENCE STEP M1 - X-IDLESCAN 120

Enter From: M19 when DE STS * ; M16 when CHAIN (entry from M16 only when not chained).

Function: Scans to find pending status in subsystem such as interrupts, device ends, etc.

Exit To: M2 at end of scan or detection of interrupt, device end, or status to be reported to CPU, raise REQIN upon exit; M3 when trapped by channel or hardware.

SEQUENCE STEP M2 — X-IDLEPEND (A PART of X-IDLESCAN 120)

Enter From: M1; M20 when SUPPRO (M20 entry only when SUPPRO from channel is inactive which indicates channel has completed its sequence).
Function: Wait for channel SEL0.

SEQUENCE STEP M3 — X-TRAP 122

Enter From: By trap only.
Function: On trap by channel, logic 150 or 151 set branch conditions in branch control 41. Microprogram scans these branch conditions to enter a microprogram corresponding to a channel command.

SEQUENCE STEP M4 — INITIAL SELECTION 125

M4A Function: Perform initializing functions as described in patents showing channel operations. 20 Below are particular functions related to concurrent diagnostics as implemented in I/O controller 11.

M4B Function: BOC Not Chained, Go to M4C; BOC Chained, skip M4C, go to M4D (maintain diagnostic mode). (Never chained on first command of a chained sequence).

M4C Function: Reset all LSR diagnostic flags. This is done on first command of any chained sequence initiated by an SIO (start I/O). See remarks of effect on concurrent diagnostics. Since chaining has been broken, CPU is indicating to I/O controller that the diagnostic procedures have been completed. Accordingly, all diagnostic flags including BLT INT are reset for enabling usual data processing operations.

M4D Function: Initial status bytes from LSR 75 are transferred to CBI with STATIN activated on CTI in accordance with patents describing channel operations. The chained condition in I/O controller 11 is reset if SUPPRO is inactive and continues set if SUPPRO is active. This enables the CPU to either selectively continue the chain or break it after execution of the command in step M5. CUB is activated in the channel interface not chained.

SEQUENCE STEP M5

Function: Detect for a rewind (REW) or data security erase (DSE).
Exit: 0 exit to M10 for executing command. 1 continue on testing chain.

SEQUENCE STEP M6

Function: Test for chained condition in an interface.
Exit: 0 exit to M9. 1 continue testing for forcing unusual conditions on interface.

SEQUENCE STEP M7

Function: Test LSR flag to see if device busy (DVE BSY) is to be sent to CPU. 1 exit to M10 for executing command. 0 perform M8.

SEQUENCE STEP M8

Function: Set LSR hold status. This status indicates a free-standing or time-consuming operation to be performed by an I/O device upon completion of

initiation of I/O device function. CU will continue to do other things and will not send ending status to channel for device until a DVE is received.

SEQUENCE STEP M9

Function: Set LSR REW/DSE FLG. This indicates to the microprogram that an REW/DSE is being performed by the addressed MTU. There is one flag for each I/O device or MTU. This flag is used during IDLESCAN 120 for checking whether or not the REW/DSE is still being performed by the addressed MTU.

SEQUENCE STEP M10

Function: Executes channel command. This may be a read, write, sense, or print in accordance with I/O subsystem functions as related to the CPU.

SEQUENCE STEP M11

Function: Sense for REW/DSE. 0 exit to M13 for assembling ending status (do not have to wait for completion of I/O device operation). 1 exit to M12.

SEQUENCE STEP M12

Function: Check for DVE from device doing REW/DSE.

Exit: 0 device has completed free-standing operation. Return to 1 for scanning activity of other devices. 1 wait loop for completion of I/O device operation.

SEQUENCE STEP M14

Function: Assemble ending status. Various indicators in LSR 75, as well as latches in CU, are sensed and assembled into a fixed number of sense bytes for transmittal to the I/O channel simultaneously with STATIN in step M15.

M14A Function: Sense for block interrupt flags, i.e., determine whether or not the unit check (UC) can be sent to channel.

Exit: 1 exit directly to M15 for sending ending status to CBI. 0 block interrupt is off, CU must check for UC condition.

M14B Function: Check LSR 75 for "send UC" flag.

Exit: 0 not UC, exit directly to M15. 1 UC condition is sensed without a block interrupt. Exit to M14C for adding UC to ending status.

M14C Function: UC sense bit in LSR status byte is set in preparation for sending UC status to channel in CPU.

SEQUENCE STEP M15

Enter: Steps M14A, B, or C.

Function: Transfer status information to CPU. Status byte from LSR 75 is supplied to CBI while simultaneously STATIN bit is activated on CTI. If SUPPRO is received from connected channel, the chaining latch in CU is set for continuing the diagnostic or chaining operation.

SEQUENCE STEP M16

Function: Check for chaining condition.

Exit: 0 return to M1 for IDLESCAN operation, i.e., all channel commanded functions have been completed. 1 continue on chained operation.

SEQUENCE STEP M17

Function: Reset all CTI's.

SEQUENCE STEP M18

Function: Check for ARM CUB flag.
Exit: 0 to M20. 1 exit to M19.

SEQUENCE STEP M19

Function: ARM CUB sets flag in LSR 75 for supplying a CUB signal in response to the next received channel command (note that chained condition is maintained).

SEQUENCE STEP M20

Function: Since chain command has been received, SUPPRO is active. Wait loop in M20 until SUPPRO is deactivated, then go to step M2.

With regard to the above flowchart, in step M4B, the CU will never be chained if the command being re-

ceived is the first command in a set of chained commands or the only command. Accordingly, the block interrupt flag (BLK INT FLG), as well as all other diagnostic flags, is reset in step M4C. To maintain the BLK INT FLG during a chained diagnostic operation for preventing the control unit from interrupting with ending device status, all SIO's must have a SET DIAGNOSE command with a channel control word (CCW) indication BLK INT FLG being set. This set of operations interlocks the diagnostics from other data processing operations which are operating concurrently. Data processing operations, whether or not chained, do not use SET DIAGNOSE; and, therefore, the BLK INT FLG will never be set during normal data processing operations. Also, upon dropping a chained condition by not supplying SUPPRO, the block interrupt and other diagnostic flags are reset enabling the CU to return to data processing operations. Accordingly, the BLK INT FLG will only be activated from the SET DIAGNOSE following an SIO to the beginning of the next SIO.

TESTING STACKABLE DEVICE STATUS

This section describes three tests in simplified flowchart form using the BLK INT FLG set forth in the microprogram flowchart. The first portions D1 and D2 set up the various tests. Test 1, steps D3-D10, concurrently tests stackable DVE STS for all devices attached to a given CU. Test 2, steps D11 through D16, tests the ability of a CU to maintain stackable status while performing other commands. Test 3, steps D17-D24, concurrently tests pending DVE STS on an SIO.

The below flowchart represents a program within a CPU connected to the CU having the microprogram flowcharted above.

Setup Tests

PROGRAM STEP D1

Function: Set DX to SIO. The address X of the first device to be tested for stackable status is set in an SIO instruction to be sent to a channel processor.

PROGRAM STEP D2

Function: SET DIAGNOSE and its CCW. The BLK INT FLG is set, together with the chaining flag.

The chaining flag causes the channel processor to supply SUPPRO upon each STATIN from CU.

Test 1 — Check Stackable DE's

This concurrent test verifies CU's ability to stack DEVICE END indications.

PROGRAM STEP D3

Function: Issue SIO instruction including issuing SET DIAGNOSE and its CCW.

PROGRAM STEP D4

Function: Cause I/O OP to be executed.

PROGRAM STEP D5

Function: Increment X to next address.

PROGRAM STEP D6

Function: Determine whether X=K, where K is a number of devices. If not, return to D3; if yes, continue to D7.

PROGRAM STEP D7

Function: SET DIAGNOSE instruction with CCW resetting BLK INT and resetting chain flag. This operation is preparing to complete the diagnostic operation enabling the CU to return to data processing functions.

PROGRAM STEP D8

Function: Issue SIO with SET DIAGNOSE set up in D7. Issue a command to the I/O program "wait."

THE WAIT MACRO

This is a macroinstruction used in OS 360 and OS 370 with regard to supervising a task, in this case, an OLT function having a subtask performed by IOS. The control program has a task control buffer (TCB) for each task in the system including the diagnostic task. The TCB has identification of the location of core storage areas allocated to such tasks. Once control has passed from the control program to the task, i.e., OLTEP or OLT, the task management programs in OLTEP keep track of the task current state. Such current state depends upon the readiness of the task program (OLT, in this case) to use the CPU. If such OLT can make immediate use of a CPU, it is READY. While it is actually using the CPU, the task is ACTIVE. The other state is WAIT. During the WAIT state, the task is inactive because more information is required from the I/O subsystem, for example. In this particular instance, the task must wait until all DE's are received from the I/O subsystem being diagnosed. The completed use of a resource, i.e., all DE's have been received, the appropriate resource manager takes control. The OLT will get control of the CPU only if higher priority tasks have been performed. Tasks controlled by initiator/terminator programs are well understood with respect to OS 360 and are not further described.

PROGRAM STEP D9

Function: This step is entered after the WAIT macro has been satisfied. The step checks to see whether or not DE's were received from all activated devices. If yes, the OLT is completed. If no, step D10 is performed.

PROGRAM STEP D10

Function: This step causes a printout of the error in that not all DE's were received. Additionally, errors may be logged in outboard data recorder (ODR) for later analysis. ODR is a programmed data log keeping operational status.

Test 2 - Concurrent Testing of Maintaining Stackable Status While Subsystem Performs Another Command

This test initiates operation to the CU in the first device. It then initiates a second operation in a second de-

vice having an extended time duration such as read/write in the burst mode. It then checks for a DE upon completion of the BURST command from the first device to see whether or not the CU stacked the DE. If it was not stacked, an error is logged.

Program steps D1 and D2 are the same except that chained instructions are different. A BURST command such as read or write, plus a control command (rewind, space OP, etc.), is performed while maintaining the BLK INT flag. This test also exercises the subsystem in an intermix situation, i.e., two devices are doing two different functions at the same time.

PROGRAM STEP D11

Function: An SIO channel command is issued followed by a SET DIAGNOSE set up in accordance with D2. Chaining is initiated.

PROGRAM STEP D12

Function: A BURST (another) command is sent to the subsystem chained to a control command on a different device.

PROGRAM STEP D13

Function: A second SIO channel command followed by a SET DIAGNOSE which resets the BLK INT FLG.

PROGRAM STEP D14

Function: In response to D13, was a CUB signal received? If yes, exit test; if no, proceed to D15.

PROGRAM STEP D15

Function: Test for DE from addressed MTU or I/O device. If DE was received, exit test. Note: A DE should be received when CUB is no. If no DE or no CUB, proceed to D16.

PROGRAM STEP D16

Function: Print detected error condition and log same within CPU for further analysis. Exit OLT.

Test 3 — Concurrent Test on Maintaining Stackable Status While Performing a Second Command

This test, by sensing for either a BUSY or DE in an SIO following a previous SIO initiating a command, concurrently tests pending DE status in the addressed CU. The test can be performed for each device; however, it is primarily a test directed toward response of a CU. BLK INT blocks SUPPRI when CU responds to a second SIO from the channel. The status resulting from the first SIO should be stored (stacked) in CU during the performance of the second SIO. This concurrent test verifies that ability.

PROGRAM STEP D17

Function: Issue SIO SET DIAGNOSE with BLK INT active as set up in D2.

PROGRAM STEP D18

Function: Initiate a command function in CU with regard to device having address X.

PROGRAM STEP D19

Function: Increment address X by 1.

PROGRAM STEP D20

Function: Issue (READ from or RECORD on tape) command to device X+1.

PROGRAM STEP D21

Function: Issue SIO to CU with SET DIAGNOSE re-setting BLK INT.

PROGRAM STEP D22

Function: Issue WAIT macro to IOS for receiving DE from device X.

PROGRAM STEP D23

Function: Check for received DE using a timeout in accordance with the length of the issued BURST command to device X+1. Go to step D24 if no DE is received; otherwise, exit Test 3 returning CPU to OS.

PROGRAM STEP D24

Function: The error is printed and logged for further error analysis by other programs.

Test 4 — Concurrent Testing Ending Control Unit End (CUE) Status on SIO (c1-C8)

This tests the capability of a CU to send a CUE upon receipt of an SIO channel command.

PROGRAM STEP C1

Function: Set a device address into an SIO instruction. SET DIAGNOSE instruction with a CCW having a BLK INT and chain a FILE OP to SET DIAGNOSE.

PROGRAM STEP C2

Function: Send SIO to CU for device DX.

PROGRAM STEP C3

Function: Send SIO FILE OP for device X.

PROGRAM STEP C4

Function: Test for CUB. If no CUB (FILE OP was not executed), print an error. If CUB is received, proceed to step C5.

PROGRAM STEP C5

Function: Time out FILE OP. At end of time out, proceed to C6.

PROGRAM STEP C6

Function: Send a second SIO to CU for device X+K, where X is the device doing the FILE OP and K is a constant for addressing a second I/O device. Then, check for responses in steps C7 and C8.

PROGRAM STEP C7

Function: Check for CUB. If CUB is received, exit test as everything is operating O.K. If no CUB, proceed to step C8.

PROGRAM STEP C8

Function: Test for CUE. If CUE has been received, exit normally. If it has not been received and CU is not busy (CUB = 0), an error should be logged since a CUE should be sent upon completion of FILE OP. Note: BLK INT being blocked permits the second and third SIO's to be performed by the CU and enables sending CUB and CUE to initiating channel for diagnostic purposes.

In a variation of the above flowcharted test, a CUB test can be performed before the FILE OP is timed out in C5. This would be an independent test of CUB.

Then, after timing out the FILE OP, the test will include a CUE test; hence, testing both CUB and CUE. Additionally, a test for DE can be provided after receiving a CUE. If the DE is not received from device X, then an error is logged.

Test 5 - Concurrent Checking Nonstackable Status (C10-C21)

In an I/O subsystem using MTU's, there are two types of status—stackable and nonstackable. Stackable status is status that can be held by the control unit while performing operations on other devices. Nonstackable status is that status that must be accepted by the CPU before another operation is initiated on the CU. Accordingly, it is important for CU to maintain nonstackable status until it is accepted by the CPU. This concurrent test tests such ability.

PROGRAM STEP C10

Function: Set device address X into an SIO instruction. Chain it to a SET DIAGNOSE with a CCW having its BLK INT FLG active. Set chaining.

PROGRAM STEP C11

Function: Issue SIO instruction with chained SET DIAGNOSE. Rewind an MTU to beginning of tape (BOT). Write one record on the tape by issuing a burst write to stop the tape. With BLK INT on, issue a backspace record (BSR). This moves tape between the first record and load point. Issue a second BSR. As a result of second BSR, CU should issue a CUE, DE, UC. With BLK INT active, UC will not be supplied to channel with the pending nonstackable status (tape is at load point and should not receive a BSR). If another MTU is addressed and was an SIO, a CUB should be received since the CU cannot complete its operation.

PROGRAM STEP C12

Function: Issue SIO to device address X+K, where K is a constant.

PROGRAM STEP C13

Function: Was a CUB received from the CU? If yes, a response has been received; proceed to C15. If no, log an error in C14.

PROGRAM STEP C14

Function: Log error detected in step C13.

PROGRAM STEP C15

Function: Issue a second SET DIAGNOSE channel command with a CCW resetting BLK INT.

PROGRAM STEP C16

Function: Issue a WAIT macro for device X in order to receive the status generated in step C11.

PROGRAM STEP C17

Function: Was appropriate status received, i.e., CUE, DE, and UC? Note: BLK INT is now erased and UC will be transferred to channel. If yes, proceed to step C19; if no, proceed to C18.

PROGRAM STEP C18

Function: Log an error based upon improper response. Note: All three responses should be received; otherwise, an error will be logged. The absence of one of the three will indicate the location of the error in the CU.

PROGRAM STEP C19

Function: Issue SIO's to device X and device X+K. At this time, both devices should be available to the CPU.

PROGRAM STEPS C20 and C21

Function: Check whether devices X and X+K are busy. If either or both are busy, log an appropriate error. If neither are busy, exit the test.

Test 6 — Concurrent Testing of Enable/Disable With and Without Pending Device Status (C30-C37)

On some I/O subsystems, there is a manually actuatable enable/disable switch. When the switch is in the enable position, operations with the connected data processing system are enabled. When the switch is in the disabled position, only off-line operations are permitted with all signal transfers to and from the data processing system being inhibited. The present test provides for concurrent testing of the enable/disable switch and its effect on pending status. An operator must intervene for actuating the enable/disable switch in accordance with instructions printed out at the operator's console.

PROGRAM STEP C30

Function: Perform steps D1-D6 of the above flowchart. This stacks DE status within the CU being diagnosed. Note: BLK INT is active.

PROGRAM STEP C31

Function: Print "drop enable" in the operator's console for an operator to switch the enable/disable switch to the disable position.

PROGRAM STEP C32

Function: Send SIO to the CU just disabled along with SET DIAGNOSE with a CCW BLK INT. This program step will not be initiated until after the operator has verified the enable/disable switch has been set to the disable position. The OLT will be keyed to a console input interrupt.

PROGRAM STEP C33

Function: Verify that the I/O subsystem appeared to be off-line. If it went off-line, an error condition occurs. The I/O subsystem must remain on-line until all stacked status has been reported to CPU. If the I/O subsystem is still enabled, as it should be, step C34 is entered without logging an error.

PROGRAM STEP C34

Function: Send SIO with a SET DIAGNOSE with the CCW resetting BLK INT.

PROGRAM STEP C35

Function: Reset all DE's in CU. This is cleared by the channel receiving all of the DE's.

PROGRAM STEP C36

Function: Supply another SIO to the I/O subsystem. The response should be from the channel processor that the I/O subsystem is now off-line. If it is not off-line, an error should be logged. In either event, proceed to step C37.

PROGRAM STEP C37

Function: Print out "set enable" to the operator's console and exit the test. The above flowchart verifies operation of the enable/disable switch, both with pending status when the I/O subsystem is not allowed to go off-line and when there is no pending status such that the I/O subsystem should go off-line upon setting the switch to the disable position.

Test 7 — Concurrent Test of all DVE BSY's on a Simultaneous Basis

This test actuates all devices on a free-standing operation such as rewind, after all the MTU's are in a rewind condition. An SIO is issued to all devices, with a busy signal being received from all of them if the operation is proper. BLK INT is necessary in order to obtain the DVE BSY signal.

PROGRAM STEP C40

Function: The test is set up in accordance with steps D1-D6 with the chained operation being rewind for all devices, plus in the SET DIAGNOSE CCW the BLK INT is activated as well as the force DVE BSY bit.

PROGRAM STEP C41

Function: An SIO is given for each and every device connected to the CU such that a rewind is initiated.

PROGRAM STEP C42

Function: A second SIO with a SET DIAGNOSE maintaining the BLK INT and force DVE BSY sent for each and every device in accordance with steps D3-D6. A DVE BSY should be received for each and every device. If not, an error is logged. If it is received, the OLT is exited with the subsystem being reset to normal conditions by a second SET DIAGNOSE resetting the BLK INT and DVE BSY flags and breaking the chain.

Test 8 — Establishing Concurrent Scope Loops Using BLK UC FLG

The subject flag is effective only for ending status, i.e., blocks interrupts for ending status only—not for intermediate status. It enables maintenance personnel, via an OLT or utility program, to enter a failing chain of CCW's that will continuously loop

in the channel independent of the CPU. That is, a channel processor has a transfer in channel (TIC) which enables a set of chained CCW's, i.e., commands, to be repeated thereby establishing a repetitive loop suitable for presenting signals on an oscilloscope. This can be done on a concurrent basis as set forth below. Repeating program loops is so well known it is not described.

Such TIC is usually broken based upon a UC interrupt and requires a second SIO to restart the commands. By suppressing the UC by setting the BLK UC FLG, the channel processor which is intermediate to the CPU and the I/O subsystem never sees the interruption condition and therefore will continuously execute the command loop at channel speeds, which are much higher than CPU channel processor I/O subsystem speeds. The I/O controller assembles ending status in a normal manner. The microprogram then proceeds to the branch operation which checks for BLK UC. Since the flag has been set by the SET DIAGNOSE CCW, normal ending status is supplied to the channel processor. The CU then returns to IDLESCAN routine awaiting the next channel processor command. With a TIC in the channel processor, the command comes almost immediately such that the command is repeated and ending status is again assembled with the process being repeated until the operator supplies a command through the operator's console to supply an SIO resetting BLK INT to the channel processor. The programs in the CPU are a utility that sets a selected command sequence that would fail with CCW BLK INT inhibiting ending status. The utility can run concurrently with data processing operations with the command being erased through the operator's console. Additionally, by manually dropping the ready condition on the device associated with the TIC loop, a UC initial status is given which is not blocked by the BLK UC FLG. This initial UC breaks the command chain and the diagnostic BLK UC stops CU from sending status at the end of a burst operation (read, write). Compare with BLK INT which inhibits sending SUPPRI.

A modification to such a utility is an automatic restart. Upon the resetting of ready by the operator, the utility could restart the device and continue on with the loop. By dropping the loop, which releases the channel processor for other operations, the concurrency reaches to the channel level, i.e., the channel can be used for diagnostic purposes during scoping; then, releasing for data processing operations by dropping ready on the addressed MTU. By raising ready, the automatic restart within the utility restarts the TIC loop for more diagnostics.

The CPU program flowcharts are encoded in MAC-ROS, such as shown below. Such macros invoke OLTEP as described in IBM Systems Reference Library, "IBM System/360 Operating System On-Line Test Executive Program," File S360-37, Form C28-6650-2, Copyright 1967, 1968, 1969, International Business Machines Corporation for program 360S-DN-533. OLTEP in turn drives 360 BAL (Basic Assembler Language) to generate machine coding. The subject flowcharts can also be implemented on a stand-alone basis, i.e., not concurrently and still use the block flag concepts.

Exemplary source statements for concurrent tests generated based upon the flowcharting including test numbers 1, 2, and 3 are:

***** * CONDITIONAL BRANCH EQUATES *****

* AFTER COMPARE INSTRUCTIONS.

BH EQU 2 .	BRANCH ON A HIGH.
BL EQU 4 .	BRANCH ON A LOW.
BE EQU 8 .	BRANCH ON A EQUAL B.
BNH EQU 13 .	BRANCH ON A NOT HIGH.
BNL EQU 11 .	BRANCH ON A NOT LOW.

The other flowcharted tests can be similarly implemented in the same manner as set forth above. Such source code is not included because it would be cumulative, rather than instructive. --

While the invention has been particularly shown and described with reference to preferred embodiments thereof, it will be understood by those skilled in the art that various changes in form and details may be made therein without departing from the spirit and scope of the invention.

What is claimed is:

1. In interfacing circuits for generating an anomalous indication from a subsystem in response to a requesting signal from a controlling data processing system interconnected with said subsystem via said interfacing circuits, means chaining said subsystem to a CPU, means supplying a flag signal,

means selectively setting a diagnostic mode, memory means for maintaining a status indication and a flag signal, means gating said status indication,

logic means responsive to said requesting signal and another signal to generate a gating signal, the improvement including in combination:

AND circuit means jointly responsive to said requesting signal and a flag signal from said subsystem to supply an enabling signal,

said subsystem capable of setting said flag signal only when chained to a CPU and in a diagnostic mode of operation,

encoding means responsive to said status indication or to said enabling signal to generate a code permutation representing said status indication, and

said gating means being responsive to said enabling signal or to said gating signal to gate said code permutation to said CPU.
